F. D. POWELL

VISIBLE INDEX

Filed Dec. 21, 1922

Inventor:

Frank D. Powell

by *Frank L. Belknap*
Atty.

UNITED STATES PATENT OFFICE.

FRANK D. POWELL, OF CHICAGO, ILLINOIS, ASSIGNOR, BY MESNE ASSIGNMENTS, TO ACME CARD SYSTEM COMPANY, OF CHICAGO, ILLINOIS, A CORPORATION OF ILLINOIS.

VISIBLE INDEX.

Application filed December 21, 1922. Serial No. 608,233.

This invention relates to improvements in visible indexes and relates more particularly to a protective tube adapted to be placed upon the folded edge of a card or sheet to protect the sheet or card, or to support the sheet or card between the flanges of a frame.

Among the salient objects of the invention are to provide a tube of folded transparent substance such as pyrolin, celluloid or the like, which may be fitted over the folded upper or lower edge of the sheets or cards and supported between the flanges of the frame, or the tubes supporting the cards may be carried by members running longitudinally of the tubes and having projections at both ends beyond the tube to engage the frame in which the card is supported; to provide tubes which hold the sheets in overlapping relation and exposing only the protected portion of the sheet while the free ends are held beneath the tubes which have their extremities sprung beneath the flanges of the frame; to provide a construction whereby entries may be made upon the card by sliding a plurality of tubes along the frame so as to expose that portion of the card available for entry.

Fig. 1 is a perspective view of a preferred type of tube showing one end and a small portion of the tube to show the folded construction.

Figs. 2 and 3 are similar views of modified forms.

Fig. 4 shows two tubes of the preferred form with the card or sheet in position and a supporting member which may or may not be used to engage the lateral flanges of the frame.

Fig. 5 is a face view of a frame carrying the tubes and folded index cards, and Fig. 6 is a cross sectional view taken on line 6—6 of Fig. 5.

Referring to the drawings, 1 is a pyrolin tube which has a doubled-back lower portion 2, and an upper face 3 beneath which the folded printed portion of the card or sheet appears. 4 is a vertical abutment portion against which the next adjoining tube contacts. 5 is a flange portion overlying the upper section of the card or sheet and serving to protect the sheet and also to hold the free end of the card or sheet in a flat position in the frame. The modified forms of

construction designated by numerals 6 and 7, have a form which is obvious by the perspective end views shown in Figs. 2 and 3.

In Fig. 4 the card or sheet 11 is folded back upon itself in two successive folds so that one face of a fold is exposed beneath the top face 3 of the tube. It will be noted that each of the tubes has this broad top transparent face through which printed matter on the folded portion serves to identify the card held by the respective tubes. These tubes and cards are adapted to be positioned beneath the flanges of card frames, not shown, but well known in this art. In certain cases the ends of the device are inserted beneath the frames, or a support member such as that shown at 12 running longitudinally through the tubes and projecting beyond the ends of the tubes to engage the frame 13 may be used for supporting the cards 11.

The positioning of the cards on the frames is somewhat different from the normal manner in supporting overlapping visible index cards on the frame. It differs in that the cards or sheets instead of having free overlapping ends, have their free ends confined or held beneath the tubes, that is, the frame is formed so as to provide a vacant space above its central web between the channels. The sheets or cards are held beneath the tubes and are positioned in overlapping relation beneath the tubes.

In order to make an entry upon one of the cards, it is necessary to separate the tube supporting this card from the adjoining card so as to expose the proper card so that the entry can be made. A vacant space at the top of the frame is left for the purpose of permitting the sliding of the tubes in this manner. When the entry has been made, the tubes may be returned to their abutting position.

The face of the frame when the tubes and cards are in position, presents a plurality of tubes through the front faces of which the printed matter on the folded portion of the cards identifies the subject matter of the cards or sheets, so that there is no printed or exposed portion of the card left unprotected, except the lowest card in the frame, which may be equipped with a protective member.

The method of mounting these protective members, and the use of the cards in connection therewith, forms no part of this invention, the novelty lying however, in the particular construction of the protective member as shown in the figures.

I claim as my invention:

1. Transparent flexible tubes adapted to support index elements in overlapping relation, each tube comprising an element having substantially parallel spaced side walls integrally connected, one of said side walls being of less width to provide a continuous slotted opening on that side, and an angular extension from the opposite wall forming a flange on the tubes, said flange functioning

to hold the separated index elements in a flat position.

2. Transparent flexible tubes adapted to support index elements in overlapping relation, each comprising spaced substantially parallel side walls having a continuous slotted longitudinal opening in one of said walls, adapted to have an edge of the index elements inserted therein, an angular extension from one wall projecting in substantially the same plane as the side wall provided with the slotted opening forming a flange for holding the index members in a flat position, and support members insertable in the tubes.

FRANK D. POWELL.
